UNITED STATES PATENT OFFICE.

GUSTAV L. JAEGER, OF NEW YORK, N. Y.

FOLDING BOX.

SPECIFICATION forming part of Letters Patent No. 317,795, dated May 12, 1885.

Application filed January 22, 1885. (No model.)

To all whom it may concern:

Be it known that I, GUSTAV L. JAEGER, a citizen of the United States, residing at New York, in the county and State of New York, 5 have invented new and useful Improvements in Folding Boxes, of which the following is a specification.

In the manufacture of collapsible boxes, wherein diagonal creases are used to afford 10 the capability of collapsement, it has been customary to form such creases directly in the body of the sides or ends. In such construction the creases are always visible, detracting from the appearance of the box; they also 15 weaken the sides or ends in which they are formed, necessitating the use of stiffening-flaps, if it be desired to securely hold the expanded box in shape. In this invention such folding creases are formed in the pasting-flaps, a diagonal crease being formed in each 20 such flap, one-half thereof being then pasted to the proper ends or sides which cover and protect such creases when the box is expanded, and act also as stiffeners to aid in maintaining the expanded box in shape. This and 25 the other features of the invention are more fully hereinafter described and claimed, reference being had to the drawings, in which—

Figure 1 represents a blank from which I 30 make my folding box. Figs. 2, 3, and 4 show the different stages through which the blank passes. Fig. 5 is a transverse section of the box when partly unfolded, the plane of section being indicated by the line $x x$, Fig. 6. Fig. 6 is a 35 plan or top view of the same. Fig. 7 is a perspective view of the box when completed. Fig. 8 is a plan or top view of the same. Fig. 9 is a plan of the partition when folded. Fig. 10 is a transverse section of the box 40 without the multiple partition, the plane of section being indicated by the line $y y$, Fig. 8.

Similar letters indicate corresponding parts.

In the drawings, the letter A designates the bottom, B B' are the ends, and D D' are 45 the sides, of the blank, which is cut out of pasteboard or other equivalent material in the form shown in Fig. 1, and which is creased in the lines $a b c d e$. The sides D D' are provided with extensions E E' E', which are 50 creased in the diagonal lines $fff'f'$, so that the outer sections, $g g' g'$, of said extensions

can be folded in, as shown in Fig. 2. These outer sections form the pasting-flaps, and after paste has been applied to them the sides D D' are folded in (see Fig. 3) and pressed down, 55 so that the pasting-flaps $g g' g'$ adhere to the ends B B'. After the paste has set the box is ready for use, since by lifting the sides D D' up to a vertical position (see Figs. 5 and 6) the ends B B' are gradually raised to a vertical position, and they are retained in this position by the contents of the box; but in order to retain them in position before the box is filled I can apply stiffening-flaps S to the ends of the box, one such flap being 60 shown as applied to the end B'. By folding this flap in, as shown in Fig. 14, the box is retained in its expanded position. A similar stiffening-flap may be applied to the end B of the box. The stiffening-flaps S are provided 65 with side extensions, $s s$, which, when the flap is folded in, engage with slots $s' s'$ in the sides of the box, so as to lock the stiffening-flap. 70

In the example shown in the drawings a folding top, C, is applied to the end B, and 75 when this top is folded down, Fig. 8, the box is closed. On the outer end of the top C is formed the locking-flap F, which is provided with a tongue, h, and if this tongue is passed into an opening, i, in the end B' the top is 80 locked. For transportation the box is folded up, as shown in Fig. 4.

The great advantage of my box is due to the great economy of its manufacture and the ease with which it can be folded and unfolded, 85 and these qualities are chiefly due to the diagonal creases $fff'f'$. By means of these diagonal creases the pasting-flaps $g g' g'$ can be readily brought in position to receive paste, and by providing a proper tool the 90 paste can be applied to all the pasting-flaps simultaneously, and after the paste has been applied the sides D D' are folded in and then the top C is brought to the position shown in Fig. 4, and by exposing the whole to pressure 95 the pasting-flaps adhere to the ends B B' and the box is ready for transportation, and when it arrives at its place of destination it can be unfolded for use almost instantaneously.

With my folding box is combined a multiple partition, G, which is capable of being folded up, as shown in Fig. 9, or to be ex- 100

panded, as shown in Fig. 7, and which, when expanded, fits the interior of the box and forms a brace whereby the box is prevented from collapsing. The construction of the 5 multiple partition is well known, and requires no further description. When this partition is placed into the box, it forms a series of cells for the reception of eggs or other articles. In the top C is a finger-hole, *j*, and 10 when the top is closed down and locked the finger-hole comes directly over one of the transverse strips of the multiple partition G, so that said strip can be grasped and the box, together with its contents, can be lifted 15 out of the packing-case and carried from one place to another. In order to render this operation feasible, it is necessary that the top C shall be securely locked in its closing position, otherwise if the box is lifted up, as shown 20 and described, the weight of the contents of the box would be liable to force the top open and the contents would become injured.

What I claim as new, and desire to secure by Letters Patent, is—

- 25 1. A collapsible box having diagonal folding creases in its pasting-flaps, substantially as described.
2. A collapsible box having diagonal folding creases in its pasting-flaps, and having 30 stiffening-flaps formed as extensions of its ends and adapted to be folded in for holding the expanded box in shape, substantially as described.
3. A collapsible box composed of a bottom

and a top, folding sides, and pasting-flaps 35 formed as extensions of two of the sides, and having diagonal folding creases formed therein, substantially as described.

4. A collapsible box composed of a bottom and a top, folding sides, pasting-flaps formed 40 as extensions of two of the sides and having diagonal folding creases formed therein, and stiffening-flaps adapted to be folded into the box and maintain it in position when expanded, substantially as described.

45 5. In a collapsible box, the combination of a top and bottom, A C, sides B B' D D', and pasting-flaps E, the latter having diagonal folding creases *f*, substantially as described.

6. In a collapsible box, the combination of 50 a top and bottom, A C, sides B B' D D', pasting-flaps E, having diagonal folding creases, *f*, and stiffening-flaps S F, substantially as described.

7. The combination of a collapsible box 55 having diagonal folding creases in its pasting-flaps, and a collapsible partition adapted to be placed therein, dividing it into compartments and maintaining it in expanded shape, substantially as described.

60 In testimony whereof I have hereunto set my hand and seal in the presence of two subscribing witnesses.

GUSTAV L. JAEGER. [L. S.]
